METHOD OF MANUFACTURING STRANDS
FOR WEAVING PURPOSES

George E. Ginn, Des Moines, Iowa

Application May 23, 1932, Serial No. 612,902

1 Claim. (Cl. 28—1)

The principal object of my invention is to provide a method of accomplishing various color effects in strands for weaving purposes. In this connection I have in mind particularly the weaving of strands of "Cellophane" or similar material into useful items.

A further object of this invention is to provide a strand for weaving purposes that has no sharp or rough edges and is of substantial body.

10 A still further object of my invention is to provide a colored strand for weaving purposes that has a different color effect on one side than on its other side.

15 A still further object of my invention is to provide a "Cellophane" strand for weaving purposes that is artistic and refined in appearance and economical in manufacture.

These and other objects will be apparent to those skilled in the art.

20 My invention consists in the method herein-after set forth, pointed out in my claim and illustrated in the accompanying drawing, in which:

Fig. 1 is a top plan view of two ribbons about 25 to be formed into a strand. The dotted lines represent the fold lines.

Fig. 2 is a cross sectional view of the two ribbons taken on line 2—2 of Fig. 1.

30 Fig. 3 is a cross sectional view of the ribbons after the outer ribbon has been folded around the other to form my strand.

Fig. 4 is a side view of one side of a finished strand.

35 Fig. 5 is a side view of the other side of the finished strand.

Fig. 6 is a top plan view of a plurality of strands in woven or braided condition.

40 "Cellophane" or the like material is now being braided and woven into many useful items. My application for United States Letters Patent on Sheeting material, filed November 16, 1931, Serial No. 575,185, fully teaches this art. However, the weaving of strands of "Cellophane" into useful products of manufacture is beset with many difficulties.

45 It is found, for instance, that "Cellophane" which is a transparent material is made in primary colors. For many products such as lamp shades, wearing apparel, screens, and like, such base colors are too heavy in appearance with the result that artistic tints and pastel shades are out of the question. Furthermore, single ribbons of "Cellophane" do not provide sufficient body for weaving purposes.

50 Rough sharp edges are also objectionable in

the finished product. In the case of lamp shades it is desirable to have a colorful exterior and a lighter interior for the reflecting of light. My invention cares for such difficulties, as will hereinafter be appreciated.

5

I first take a ribbon of "Cellophane" or like. On this ribbon I place a second ribbon having a width approximately one-fourth of the first ribbon, as shown in Fig. 1.

I have used the numeral 10 to designate the 10 smaller width ribbon and the numeral 11 to designate the larger width ribbon. The ribbon 10 is so placed on the ribbon 11 that its inner edge rests approximately on the center 16 of the ribbon 11, as shown in Fig. 1. For best results it is recommended that the ribbon 11 be about four times the width of the ribbon 10.

With the ribbons of "Cellophane" in positions as above described, the folding operation is now in order. The outer left edge portion of the 20 ribbon 11 is folded over upon itself in such a manner that its edge rests near the center line 16. This folded portion of the ribbon 11 is designated by the numeral 12 and the portion of the ribbon 11 that is lapped by the portion 12 is designated by the numeral 14.

25 The outer right side portion of the ribbon 11 is folded over upon itself in such a manner that its edge rests also near the center line 16. This folded portion of the ribbon is designated by the 30 numeral 13 and the portion of the ribbon 11 that is lapped by the portion 13 is designated by the numeral 15.

35 As the ribbon 10 was resting on the portion 15, it will be now positioned between the portions 13 and 15. The last folding operation is the folding of the ribbon 11 on its center line designated by dotted lines and the numeral 16. These operations produce a flat elongated strand of desirable body, as shown in Fig. 3.

40

Such strands may be woven or braided in any suitable manner for the making of desirable merchandise. In Fig. 6 I designate each of the various woven or braided strands by the numeral 17. It will be noted from Fig. 3 that all rough, 45 sharp edges have been eliminated.

All kinds of various and pleasing shades and color effects can be obtained by the selecting of different colors for the ribbons 10 and 11. Shades can be made lighter or darker, but no doubt in 50 most instances, the more delicate shades will be desired for the reason that delicate tints are impossible in ordinary woven "Cellophane". A single ribbon of colored "Cellophane" may have 55 the appearance of being very light in color, but

when it is woven it gives an entirely too heavy color for such items as lamp shades and the like. In view of this, the ribbon 11 is usually of clear "Cellophane", termed as "silver Cellophane", due 5 to its silver appearance when reflecting light rays. This silver sheen is highly desirable and is especially desirable for the reflecting of light when the woven strands of "Cellophane" are made into a lamp shade. If the ribbon 10 is of a base color 10 the silver ribbon 11 embracing it will make a weavable strand of pleasing color and one that is much lighter in tint than the tint of the inner ribbon 10.

Naturally, the more times the silver ribbon 11 laps a side of the ribbon 10 the lighter will be 15 the color shade of the strand. When the ribbon 11 is folded around the ribbon 10, as shown in Fig. 3, the ribbon 10 will have on one of its sides one thickness of the ribbon 11 and on its other 20 side three thicknesses of the ribbon 11. The side having the three thicknesses to one side of the ribbon 10 will be much lighter in color than the other side of the strand. Therefore, in the weaving of lamp shades and the like the strands are 25 so woven that the three folded portions 12, 13, and 14 are on the inside of the lamp shade and the portion 15 is on the outside of the lamp shade. This provides a lamp shade having a substantial 30 color appearance on its outside and a satisfactory silver or clear appearance on its inside for the reflecting of light rays. Fig. 4 shows the lighter 35 inside of the strand and Fig. 5 shows the dark outer side of such a strand. However, the selection and blending of colors is left to the option of the user employing my method.

Various colored strands may be used in the weaving of items, such as shown in Fig. 6. It is recommended, however, that when different colored strands are used that in each instance the 40 embracing ribbon 11 be of the same color. In the case of the use of a transparent silver rib-

bon for the ribbon 11 the complete manufactured item will possess a uniform color sheen, which in this case would be silver, regardless of the individual colors of the strands.

From the foregoing it will readily be seen that 5 I have provided a very desirable method of making strands for weaving purposes.

Although I have described my method as particularly adapted to the use of "Cellophane" or like, it may be used to equal advantage with 10 other material when the embracing ribbon 11 is translucent or transparent.

I claim:

The method of producing a "Cellophane" weaving strip having a different color appearance on 15 its two sides, consisting in the taking of a flat colored transparent ribbon of "Cellophane" having substantial width, the placing thereon of a transparent "Cellophane" ribbon of a different color and of a width approximately one-fourth 20 of the width of said first-mentioned ribbon; the positioning of said second-mentioned ribbon on said first-mentioned ribbon whereby said first-mentioned ribbon will extend approximately one-quarter beyond one marginal edge of said second 25 ribbon and approximately two-quarters beyond the other marginal edge of said second ribbon, the folding of the approximately one-quarter of the first-mentioned ribbon onto and over said second ribbon, the doubling of the approximately two-quarters of said first ribbon back upon itself, and lastly the folding of the portion of the first ribbon that is doubled back upon itself onto and over the one-quarter portion of said first ribbon that was folded upon said second ribbon, 35 thus producing three thicknesses of said first-mentioned ribbon on one side of said second-mentioned ribbon and one thickness of said first-mentioned ribbon on the other side of said second-mentioned ribbon.

GEORGE E. GINN.
